UNITED STATES PATENT OFFICE

155,083

DESIGN FOR AN ASH TRAY

Samuel K. Frank, Wheeling, W. Va.

Application October 18, 1948, Serial No. 149,149

Term of patent 14 years

(Cl. D85—2)

To all whom it may concern:

Be it known that I, Samuel K. Frank, a citizen of the United States, residing at 1213 Main Street, Wheeling, West Virginia, have invented a new, original, and ornamental Design for an Ash Tray, of which the following is a specification, reference being had to the accompanying drawing, forming part thereof.

Figure 1 is a perspective view of an ash tray showing my new design.

Figure 2 is a vertical section of the same.

I claim:

The ornamental design for an ash tray, as shown.

SAMUEL K. FRANK,
